UNITED STATES PATENT OFFICE.

CYRUS HAMLIN, OF NEW YORK, N. Y.

THUMB-REST FOR VIOLINS AND SIMILAR MUSICAL INSTRUMENTS.

1,144,194.

Specification of Letters Patent. Patented June 22, 1915.

Application filed January 5, 1914. Serial No. 810,346.

To all whom it may concern:

Be it known that I, CYRUS HAMLIN, a citizen of the United States, and a resident of the city of New York, borough of Brooklyn, in the county of Kings and State of New York, have invented a new and Improved Thumb-Rest for Violins and Similar Musical Instruments, of which the following is a full, clear, and exact description.

10 The object of the invention is to provide a new and improved thumb rest for violins and similar musical instruments arranged to permit the player to readily finger the strings for high notes at the same time permitting holding the fingers in correct position for pressing the strings forcibly down onto the finger board.

20 In order to accomplish the desired result use is made of a thumb rest arranged on the front end of the body to one side of the neck of the violin and adjacent to the face of the body to allow the thumb of the fingering hand of the player to readily pass from the neck under the said thumb rest to partially support the instrument and from the thumb rest back onto the neck.

30 A practical embodiment of the invention is represented in the accompanying drawings forming a part of this specification, in which similar characters of reference indicate corresponding parts in all the views.

35 Figure 1 is a plan view of the thumb rest as applied to a violin, parts being shown in section; Fig. 2 is a cross section of the same on the line 2—2 of Fig. 1; Fig. 3 is a sectional side elevation of the thumb rest; Fig. 4 is a plan view of a modified form of the thumb rest as applied to a violin; and Fig. 5 is a side elevation of the thumb rest shown 40 in Fig. 4.

The thumb rest illustrated in Figs. 1, 2 and 3 is in the form of a plate A located at the forward end of the body B of the violin adjacent to one side of the neck C of the violin so that the player can readily pass the thumb from the under side of the neck to the under side of the plate A to allow the player to reach with the fingers onto the strings when it is desired to play high notes, 45 and to permit the player to hold the fingers in the correct position relative to the strings, that is, approximately vertical thereto, to allow of pressing the strings forcibly down onto the finger board, the plate A forming a stop member so as to allow of a greater pressure on the strings than if the end of the

thumb were merely resting against the neck. The plate A is preferably arched, as plainly indicated in Figs. 2 and 3, and the rear edge fits against the front end of the body B 60 while the inner side of the plate A reaches onto the corresponding side of the neck C so that the thumb can readily slip from under the neck C onto the under side of the plate A or back from the latter to the usual 65 normal position on the neck C.

In order to secure the plate A in the position described, use is made of a transverse bar D extending integrally from the top of the plate A at the inner end thereof to then 70 pass under the finger board E to the other side of the neck, and the bar at this end is provided with an angular offset D' provided with screws F engaging a clamping plate G provided with a lining H of felt or other 75 suitable material engaging the side of the neck C, as plainly indicated in Figs. 1 and 2.

In the modified form shown in Figs. 4 and 5, the plate A' forming the thumb rest is provided on the top with an angular member I adapted to rest on the top of the body B of the violin, and the lower end of the said member I is provided with a threaded end I' on which screws a nut J in which screws a rod K having an angular clamping 80 member K' adapted to engage the under side of the body B. The threaded parts I' and K have their threads running in opposite directions so that when the nut J is turned in one direction the clamping members I and K' firmly engage the top and bottom of the body B to securely fasten the plate A' in position at the front end of the body B adjacent to one side of the neck C.

90 From the foregoing description of the 95 various parts of the device the operation thereof may be readily understood. When the musician is playing in some of the upper positions, more especially in the fifth position, it is necessary to bring the thumb out 100 from under the neck in order that the fingers may reach over the strings, especially when playing upon the upper portions of the G and D strings near the upper end of the finger board. The thumb, when playing 105 in these upper positions, lies just beneath the plate A so that the violin can be partially supported on the thumb, thus giving the fingers free play. Furthermore, since the plate forms a stop member the fingers 110 may be brought down with greater force than can be exerted when the plate A is not

present. It may be stated further that the length of the fingers of different persons varies and that for a person whose fingers are short this device is useful in that it permits the shifting of the thumb away from the neck entirely so that the hand can be held farther over the finger board and thus persons with short fingers may readily reach the upper positions.

10. From the foregoing it will be understood that I do not limit myself to the particular fastening means employed for fastening the thumb rest A or A' in position on the violin, but it is of the utmost importance that the 15 thumb rest A be located at the point mentioned to accomplish the desired result.

Having thus described my invention, I claim as new and desire to secure by Letters Patent:

20. 1. In combination with a musical instrument having a neck, a thumb rest in the form of a plate, and means for fastening the said thumb rest to the instrument in contact with the forward end of the instrument 25 and projecting laterally from one side of the neck thereof, the inner side of the rest being contiguous to the adjacent side of the neck to allow the thumb of the fingering hand of the player to readily pass from under the 30 neck to the under side of the said rest and from the latter back onto the neck.

2. In combination with a musical instrument having a neck, a thumb-rest, means for fastening the said thumb rest to the instrument 35 at the forward end of the instrument body and to one side of the neck of the instrument, the said rest being in the form of a plate, the inner side of which extends onto the adjacent side of the neck, and the said 40 fastening means comprising a transverse bar extending from the top of the plate over the top of the body and under the finger board, the bar terminating in an angular offset, screws in the said offset, and a clamping 45 plate engaged by the said screws and pressed against the corresponding side of the neck.

Copies of this patent may be obtained for five cents each, by addressing the "Commissioner of Patents.
Washington, D. C."

3. The combination with a musical instrument having a neck, of a laterally extending plate curved to fit the thumb, said plate being at the forward end of the body and to 50 one side of the neck of the instrument, and means extending underneath the finger board for securing said plate in position.

4. The combination with a musical instrument having a neck, of a laterally extending 55 plate curved to fit the thumb, said plate being at the forward end of the body and to one side of the neck of the instrument, and means extending underneath the finger board for securing said plate in position, 60 said last named means comprising a U-shaped bar, one end of said U-shaped bar being provided with means for fastening the same 65 to the neck of the instrument on the opposite side thereof from the curved plate.

5. In combination with a musical instrument, having a neck, a laterally projecting thumb rest in the form of a curved plate, 70 said rest being disposed at the forward end of the body of the instrument and contiguous to one side of the neck thereof, and means for securing said thumb rest in position.

75. 6. A thumb rest for musical instruments having necks, comprising a curved plate having an angular member projecting from its top adjacent to one end thereof, and means coacting with the angular member of 80 the plate to secure the said plate to an instrument at one side of and contiguous to the neck at the forward end of the body.

In testimony whereof I have signed my name to this specification in the presence of 85 two subscribing witnesses.

CYRUS HAMLIN.
